(57) **CLAIM**

The ornamental design for a display screen or portion thereof with graphical user interface, as shown and described.

DESCRIPTION

FIG. 1 is a front view of a display screen or portion thereof with graphical user interface showing our new design in a first embodiment;

FIG. 2 is an enlarged view of the portion of the first embodiment shown within the area designated as 2 in FIG. 1;

FIG. 3 is a front view of a display screen or portion thereof with graphical user interface showing our new design in a second embodiment; and,

FIG. 4 is an enlarged view of the portion of the second embodiment shown within the area designated as 3 in FIG. 3.

The outer broken lines in FIGS. 1 and 3 show a display screen or portion thereof, and form no part of the claimed design. The other dash-dot broken lines show portions of the graphical user interface that form no part of the claimed design. The dot-dash lines in FIGS. 1 and 3 and the dot-dash lead lines labeled "2" and "4" respectively show the areas from which the enlargements in FIGS. 2 and 4 are taken and form no part of the claimed design.
